Primary Examiner — Robert M Spear*Assistant Examiner* — Ryan Harvey(74) *Attorney, Agent, or Firm* — Crossley Patent Law(57) **CLAIM**

The ornamental design for a rolling abdominal exerciser, as shown and described.

DESCRIPTION

FIG. 1 is a front elevation view of a rolling abdominal exerciser showing my new design;

FIG. 2 is a rear elevation view thereof;

FIG. 3 is a right side elevation view thereof, the opposite side being a mirror image of the shown;

FIG. 4 is a top plan view thereof;

FIG. 5 is bottom plan view thereof; and,

FIG. 6 is an isometric view thereof.
